UNITED STATES PATENT OFFICE.

MARTIN LUTHER WEAVER, OF MONTGOMERY, ALABAMA.

WINDOW-VENTILATOR.

1,100,640.

Specification of Letters Patent.

Patented June 16, 1914.

Application filed October 22, 1913. Serial No. 796,668.

To all whom it may concern:

Be it known that I, MARTIN LUTHER WEAVER, a citizen of the United States, residing at Montgomery, in the county of 5 Montgomery and State of Alabama, have invented new and useful Improvements in Window-Ventilators, of which the following is a specification.

The invention provides an attachment 10 which may be readily fitted to any window to direct a portion of the air blowing substantially parallel with such window through the latter into the room, apartment or other place to be ventilated.

15 The invention consists of a deflector adapted to be projected outward from the window, and a frame of peculiar form having such deflector attached thereto and retained in place between the sill and sash, 20 the latter being lowered upon the frame to clamp the same in the required position.

The invention consists of the novel features, details of construction and combination of parts, which hereinafter will be 25 more particularly set forth, illustrated in the accompanying drawing, and pointed out in the appended claims.

Referring to the drawing, forming a part 30 of the specification, Figure 1 is a front view of a window provided with a ventilator embodying the invention. Fig. 2 is a detail view in perspective of the attachment.

35 Corresponding and like parts are referred to in the following description, and indicated in all the views of the drawing, by the same reference characters.

The deflector 1 is provided at its upper and lower edges with outwardly flared wings 2, which serve to confine the air and 40 insure a good proportion thereof passing through the window into the room or place to be ventilated. The wings 2 may form a part of the deflector or may be attached thereto in any manner. The deflector may 45 be constructed of metal or other suitable material.

The frame to which the deflector is attached comprises uprights 3, cross pieces 4 and braces 5 and 6. The braces 5 are 50 attached at their lower ends to the uprights 3 and are secured at a point between their ends to the braces 6. The upper ends of the braces 5 terminate about in line with the upper ends of the uprights 3 so as to touch 55 the lower rail of the sash between which

and the sill of the window the device is clamped. An upright 7 intermediate of the uprights 3 is secured to the cross bars 4 and has the deflector 1 secured at its inner vertical edge thereto. The braces 6 are connected at their outer ends to the deflector and at their inner ends to the frame. 60

When the deflector is in position it projects outward from the window opening and is arranged intermediate of the jambs 65 so that a current of air blowing across the window opening in either direction will strike the deflector 1 and be directed into the room, apartment or similar place to be ventilated. The lower ends of the uprights 70 3 rest upon the sill and the sash is adjusted so that the lower cross piece comes between and engages the upper ends of the uprights 3 and braces 5, thereby holding the frame and device in position. 75

From the foregoing description, taken in connection with the accompanying drawing, the advantages of the construction and of the method of operation will be readily apparent to those skilled in the art to which 80 the invention appertains, and while I have described the principal of operation of the invention, together with the device which I now consider to be the best embodiment thereof, I desire to have it understood that 85 the device shown is merely illustrative, and that such changes may be made when desired as are within the scope of the claims appended hereto.

To prevent slipping of the device spurs 90 8 are provided at the lower ends of the uprights 3 to enter the sill or lower part of the window frame.

Having thus described the invention what is claimed as new, is:— 95

1. A window ventilator comprising a deflector adapted to be projected from the window opening, and a frame for supporting the deflector from the window opening, said frame comprising up-rights, cross pieces 100 connecting the up-rights, braces attached at their lower ends to the up-rights and inclining outwardly therefrom to receive the lower edge of the sash between the up-rights and the braces, and other braces attached to the up-rights and the first-mentioned braces and having connection with the deflector. 105

2. In combination, a deflector, up-rights, cross-pieces connecting the up-rights, braces 110

attached at their lower ends to the up-rights and inclining at their upper ends away from the up-rights, lateral braces attached at their inner ends to the up-rights and the 5 first-mentioned braces, and a deflector attached to the cross-pieces and to the outer ends of the lateral braces.

In testimony whereof I affix my signature in presence of two witnesses.

MARTIN LUTHER WEAVER.
